(57) **CLAIM**

The ornamental design for a tube assembly and connector, as
shown and described.

DESCRIPTION

FIG. 1 is a front, right side and top perspective view of a tube
assembly and connector showing our new design.

FIG. 2 is a rear, left side and top perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof, enlarged for clarity; and,
FIG. 8 is a rear view thereof, enlarged for clarity.

The broken lines in the drawings illustrate portions of the
tube assembly and connector and form no part of the claimed
design.

The break lines in FIGS. 1-6 indicate that the appearance of
any portion of the tube assembly and connector between the
break lines forms no part of the claimed design.
